Des. 221,562
Patented Aug. 24, 1971

221,562

CONSOLE

John H. Jordan, Jr., 8124 S. Crandon Ave.,
Chicago, Ill. 60617

Filed Feb. 6, 1970, Ser. No. 21,311

Term of patent 14 years

Int. Cl. D6—01

U.S. Cl. D33—19

FIG. 2.

FIG. 1.

FIG. 3.

FIG. 4.

FIG. 5.

FIG. 6.

FIG. 1 is a plan view of a console showing my new design;

FIG. 2 is a front elevation of the console;

FIG. 3 is an elevation showing the left end of the console;

FIG. 4 is an elevational view showing the right end of the console;

FIG. 5 is an end elevation similar to FIG. 3, but with a drawer pulled partly out of the console; and

FIG. 6 is an end elevation similar to FIG. 4, but with a center door swung open.

The under surface of the console is conventional while the back surface thereof is plain and unornamented.

I claim:

The ornamental design for a console, as shown and described.
